RECOVERY OF LIQUID HYDROCARBONS
FROM DISTILLATE WELLSGeorge S. Bays, Tulsa, Okla., assignor to
Stanolind Oil and Gas Company, Tulsa, Okla.,
a corporation of Delaware

Application September 29, 1938, Serial No. 232,401

6 Claims. (Cl. 62—175.5)

This invention relates to the recovery of liquid hydrocarbons from distillate wells.

In recent years it has become increasingly frequent to encounter deep producing formations under high pressures, such as 2000 to 5000 pounds per square inch, for instance 3000 pounds per square inch, which are characterized by the fact that the fluids entering the base of the well are wholly or largely in the vapor phase. The fluids from these distillate wells contain substantial quantities of normally liquid hydrocarbons.

It is an object of this invention to provide new and improved methods and apparatus for the recovery of these normally liquid hydrocarbons.

Another object of my invention is to increase the amount of these normally liquid hydrocarbons which can be recovered economically. A further object of my invention is to provide methods and apparatus which will permit low temperature operation with an accompanying improvement in recovery.

Other and more detailed objects, advantages and uses of my invention will become apparent as the description thereof proceeds.

In dealing with a mixture of hydrocarbons in the vapor phase it is true in general that as the pressure is increased from atmospheric upwards at a given temperature, a point is reached at which the heavier hydrocarbons begin to condense out in the liquid phase. Furthermore, as the pressure increase is continued the amount of condensation likewise increases. However, a peculiar phenomenon has been observed at high pressures and within certain temperature ranges. As the pressure is increased a point is ultimately reached at which no further condensation occurs and beyond which liquid actually tends to vaporize, thus reducing the amount of liquid phase present. This is due to the phenomenon called retrograde vaporization.

Looking at this same phenomenon from the opposite point of view, we may take a mixture of hydrocarbons, for instance the total production of a distillate well in the vapor phase at a high pressure, for instance 3000 pounds per square inch, and gradually lower the pressure isothermally until a liquid phase commences to form. This formation of a liquid phase may be referred to as retrograde condensation since it is condensation under decreasing pressure conditions while normally liquids condense from the vapor phase when the pressure is increased rather than decreased. Further decreasing the pressure on the system referred to increases the amount of liquid phase formation until a point is reached at

which the liquid phase formation reaches a maximum and this point is referred to herein as the optimum retrograde condensation pressure. Further decrease of the pressure decreases the amount of liquid phase present until ultimately a point is reached under low pressure conditions where the total hydrocarbons are in the ordinary vapor phase condition. The value of the optimum retrograde condensation pressure depends, of course, on the composition of the hydrocarbon mixture used and is also somewhat dependent on the temperature at which the system is maintained although for considerable ranges of temperatures the optimum retrograde condensation pressure remains approximately constant.

As an example of the retrograde condensation phenomenon, if the pressure be increased upon a gas and oil system, condensation of, say, hexane will occur up to a given point, possibly in the neighborhood of 600 pounds per square inch at the particular temperature in effect, for instance 100° F. When the pressure is increased beyond this point, retrograde vaporization takes place and the hexane in the oil body commences to re-enter the vapor phase.

My invention utilizes this phenomenon in the production of liquid hydrocarbons from distillate wells. After recovery of the liquid hydrocarbons the remaining gases are preferably recompressed and recycled to the formation from which they were produced and the method is thus applicable to the secondary recovery of oil from partially depleted oil reservoirs since the recycled hydrocarbons under high pressure tend to pick up additional liquid phase hydrocarbons by virtue of the retrograde vaporization phenomenon and thus can be recovered continuously.

For instance, in practicing my invention a hydrocarbon gas, preferably natural gas, is injected into the partially depleted reservoir under high pressure through one or more wells which need not be closely spaced—for instance, spacing as high as one injection well per 160 acres can be used. The pressure ultimately reached must exceed the optimum retrograde condensation pressure by a substantial margin, preferably at least 1000 pounds per square inch. The pressure used can be as high as desired, the main limiting factor being the cost of producing and maintaining excessive pressures. In general I prefer to raise the pressure in the reservoir to a value between about 2500 pounds per square inch and about 5000 pounds per square inch.

The gas is allowed to remain in contact with the oil in the partially depleted reservoir at this

pressure for a period of at least several days and preferably several months to permit approximate equilibrium to take place within the very fine pores and capillaries of the reservoir.

5 When this period has been allowed in order to achieve approximate equilibrium, gas is produced from the formation. This gas may be produced from the same wells through which it is introduced and this constitutes an additional advantage over, and distinction from, gas drive and water drive methods which necessarily use separate wells for the driving fluid and the oil produced, but as will hereinafter appear I can, and it is often desirable to, operate on a continuous 10 basis using separate injection and production wells.

The gas is produced at as near reservoir pressure as practicable. In any event the pressure in the formation surrounding the well or wells 15 from which the gas is produced is preferably not allowed to drop below about 2500 pounds per square inch. It is also desirable that the pressure within the well itself be maintained above these pressures but this is not always essential 20 since condensation within the well results in entrainment and the liquid thus separating out is not lost as it would be if the condensation occurred within the underground formation.

Due to the retrograde vaporization phenomenon, the gas produced under high pressure contains normally liquid hydrocarbons from the underground formation which were dissolved in the gas by virtue of the high pressure. These hydrocarbons can be separated from the gas by merely 25 lowering the pressure to some value equal to or above the optimum retrograde condensation pressure, for instance a pressure of from about 400 pounds per square inch to about 1200 pounds per square inch, and preferably from about 600 30 pounds per square inch to about 1000 pounds per square inch, and then separating the vapor and liquid phases. If the pressure is lowered below the optimum retrograde condensation pressure, the liquid phase commences to enter the vapor 35 phase which is usually undesirable. However, although operation slightly below the optimum retrograde condensation pressure yields less total liquid hydrocarbons, there is an increased concentration of butanes and heavier hydrocarbons 40 in the liquid phase and this makes it possible to recover additional amounts of these desirable hydrocarbons by operating at pressures lower 45 than the optimum retrograde condensation pressure but above 400, or preferably 600, pounds per square inch as above indicated.

It is highly desirable in accordance with my invention to cool the fluids passing from the well by indirect heat exchange as well as by the Joule-Thomson effect which accompanies the pressure 50 reduction since in this way much greater yields of butanes and heavier hydrocarbons can be obtained as will hereinafter appear.

While it is possible, as above mentioned, to use the same well for the introduction and withdrawal of gas in accordance with my invention this necessitates discontinuous operation and it is greatly preferable to use different wells.

My invention will be described with particular reference to the accompanying drawings in which 60 Figures 1 and 2 represent, in diagrammatic form, alternative embodiments of my invention.

A simplified and highly diagrammatic illustration of one type of equipment for practicing my invention is shown in Figure 1. In operating 65 in accordance with Figure 1, gas is introduced at

high pressure into well A, passes through the partially depleted oil reservoir 10, which is isolated by impervious strata 11 and 12, and by brine barrier 13, passes into well B at high pressure, is withdrawn from well B through line 14, 5 and has its pressure and temperature reduced to form a liquid phase by virtue of the retrograde condensation effect. This liquid phase is removed by means of separator 15, the gas is recompressed and then reintroduced into well A. 10

The gas introduced into well A can be composed in whole or in part of recycle gas withdrawn through well B as we have just seen, or all or part of it can come from a separate source, for instance valved line 28. In any event, an extraneous gas is usually necessary for make up purposes, since there is inevitably some slight loss. The gas introduced is constituted wholly or at least predominantly of one or more hydrocarbons having one or two carbon atoms per molecule. 20 Usually methane is the main constituent, but ethane can be used. Natural gas, or other mixtures of methane and ethane, with or without minor quantities of heavier hydrocarbons, are the most suitable and available materials for use in 25 practicing my invention.

This gas can be introduced at any pressure above about 2500 pounds per square inch but substantially higher pressures are desirable to provide pressure drops since these figures represent the minimum pressures which should be built up within the reservoir. In any event, of course, the injection pressure must be well above the formation pressure.

As previously indicated the gas picks up heavier 35 hydrocarbons (largely propane to heptane) from the otherwise unproducible oil films existing within the partially depleted oil reservoir 10, and then issues through well B and line 14. The pressure is reduced by means of pressure reduction valve 16 to a valve in the neighborhood of the optimum retrograde condensation pressure or in other words, to a pressure of from about 400 pounds per square inch to about 1200 pounds per square inch, and preferably from about 600 40 pounds per square inch to about 1000 pounds per square inch.

This pressure reduction is, of course, accompanied by a temperature reduction and this temperature drop causes further amounts of liquid 50 phase to separate. However, in order to secure really efficient operation with production of an optimum quantity of the total normally liquid hydrocarbons present in the well fluids, it is highly important that additional cooling be used 55 since the cooling available by virtue of the Joule-Thomson effect is very limited.

As an example of the importance of separating liquid hydrocarbons at low temperatures a typical distillate well fluid (Katy Field, Texas) 60 contains 1.181 gallons of hydrocarbons having more than four carbon atoms per 1000 cubic feet (at 60° F., 14.7 pounds per square inch absolute) of hydrocarbon gas composed of hydrocarbons having three or less carbon atoms. This fluid 65 will precipitate 68.0 per cent of these heavier hydrocarbons when trapped at 1000 pounds per square inch and 80° F., but when trapped at the same pressure and 0° F., 78.7 per cent of the heavier hydrocarbons will be precipitated.

70 However, when operating with the apparatus shown in Figure 1, a limiting factor with reference to the temperature which can be used is the formation of the so-called natural gas hydrates which occurs at a temperature varying 75

with the pressure used and the composition of the hydrocarbons produced. Thus, it is preferred in accordance with Figure 1 that the temperature at which the liquid phase is separated and removed be from about 25° F. to about 150° F. but preferably from about 50° F. to about 75° F., or, otherwise stated, above, but preferably within about 10° F. of, the melting point of the natural gas hydrates formed with the particular well fluids under consideration at the separation pressure used in accordance with my invention.

Temperature adjustment is obtained by means of cooler 17 which should precede pressure reduction valve 18, since in this way the cooling medium used can be of higher temperature and refrigeration is much less expensive than if the external cooling were applied after the expansion of the well fluid, which is accompanied by cooling occasioned by the Joule-Thomson effect.

Following pressure and temperature adjustment, the fluids enter separator 15, which can be of any conventional type. From this separator the liquid phase, separated by virtue of the retrograde condensation phenomenon is removed through valve 18, which is responsive to liquid level control 19, and then passes through line 20 to storage, or to a fractionation system, or a trap system of stage separation for removal of methane and ethane which can be recycled.

Gas, stripped of a major portion of its components heavier than ethane, passes through back pressure valve 21. It can then be sent through valve 22 and line 23 to a further recovery system of conventional type, wherein additional quantities of hydrocarbons heavier than ethane can be removed by methods such as refrigeration, charcoal adsorption, or oil absorption. After passing through this supplemental recovery system the dry gas can be reintroduced into well A.

However, the retrograde condensation phenomenon, properly utilized, suffices to recover the great bulk of the valuable heavier hydrocarbons and the gas from separator 15 can be, and preferably is, recycled directly to well A through valve 24 and compressors 25. It will be seen that by opening valve 26 and closing by-pass valves 27, the compressors can be used in series, while by closing valve 26 and opening the by-pass valves, 50 they can be used in parallel.

In Figure 2 I have provided a system which has numerous advantages over that of Figure 1 but which utilizes the same general principles and is applicable, like the system of Figure 1, to either 55 primary or secondary recovery, but while Figure 1 was described with particular reference to secondary recovery Figure 2 will be described with particular reference to primary recovery.

Producing well B is a well of the distillate type 60 and the well head pressure may suitably be from about 2000 to about 5000 pounds per square inch, typically 3000 pounds per square inch. The well head temperature (at well head pressure) will be above 100° F. and usually above 125° F., for instance 150° F. The fluids produced by the well will normally contain some liquid phase material due to the fact that some small amount of the total products may enter the bottom of the well in the liquid phase but due more particularly to 65 the fact that in its upward progress in the well the fluid encounters a pressure reduction and a temperature reduction which both tend to precipitate liquid phase material.

The well fluids pass through valve 100 which 70 is normally wide open and, therefore, does not

serve to give any substantial pressure reduction and, thence, preferably through cooler 101 which may, for instance, lower the temperature of the well fluids to, for instance, 100° F. or some other temperature above that at which hydrates form under these conditions. The cooled fluids, if cooler 101 is operated, pass into separator 102 in which the liquid phase entering the base of the well, that formed in the upward passage through the well and that formed in cooler 101 are separated out and are withdrawn through valve 103 controlled by liquid level controller 104 and pass through line 105 to separator 106. The gases from separator 102 pass out through line 107 and a small amount of antifreeze solution which can, for instance, be a calcium chloride solution or other brine, glycerine, glycol or the like, is injected into the line under the control of valve 108. The gases carrying the anti-freeze material, the purpose of which is to avoid clogging of the apparatus by natural gas hydrates, pass through three successive coolers 109, 110 and 111 although it is to be understood that other cooling arrangements can be used. As shown, cooler 109 operates by indirect heat exchange with the low temperature liquids from separator 106, cooler 110 operates by indirect heat exchange with the low temperature gases from separator 106 and cooler 111 operates by indirect heat exchange with an external cooling medium which can be cold water or 20 brine, or ammonia or other refrigerant supplied by a conventional refrigeration cycle.

With the arrangement as hereinbefore described, and when operating with a produced well fluid which is high in moisture content, it is possible that there will be enough moisture contained in the liquids precipitated in separator 102 to cause formation of gas hydrates in line 105 after the considerable pressure drop which occurs at valve 103. To provide for this contingency, an 40 additional antifreeze line 112 is shown, passing through injection control valve 113 and into line 114 as it leaves producing well B, and before it enters cooler 101.

While the above and subsequent descriptions of 45 these processes refer to use of a recycled and re-concentrated liquid antifreeze solution, it is not imperative that the prevention of hydrate formation be handled in this manner. For instance, it is possible to use a gaseous antifreeze material, which may be recovered and recycled, and it is also possible, although much less advantageous to use a drying apparatus using the principle of adsorption, to eliminate the hydrate-forming 50 tendencies of the gas.

The cooled fluids which can suitably be at a temperature of from about -25° F. to about +75° F., or preferably from about 0° F. to about +60° F., pass through line 115 and valve 116 and are expanded into separator 106. The pressure in separator 106 is controlled by valve 117 leading to line 118 for ultimate reinjection through well A. The main pressure drop between separators 102 and 106 is across valves 103 and 116.

The pressure in separator 106 can, for instance, be the optimum retrograde condensation pressure or slightly lower but, when operating on a recycling basis, I find it preferable to use pressures somewhat in excess of the optimum retrograde condensation pressure since these higher pressures result in lower recompression costs. When recycling gas to input well A the pressure in separator 106 can, for instance, be from about 60 800 pounds per square inch to about 1500 pounds per square inch, for instance 1000 pounds per 70 75

square inch, although as previously indicated, pressures down to 600 or even 400 pounds per square inch can be used.

The pressure reduction is, of course, accompanied by a temperature reduction due to the Joule-Thomson effect and the temperature in separator 106 (which should, of course, be suitably insulated) can be from about -50° F. or preferably from about -35° F. to about $+25^{\circ}$ F. These low temperatures, made possible by the use of antifreeze, result in vastly improved recovery of butanes and heavier hydrocarbons but higher separator temperatures can be used as previously described in connection with Figure 1.

15 The pressure and temperature reduction result, of course, in the formation of additional quantities of distillate and, together with the antifreeze material, settle to the bottom of separator 106 and there stratify since the aqueous antifreeze material is substantially hydrocarbon insoluble. The lower layer of antifreeze 119 is withdrawn through water leg 120 into trap 121.

16 The upper layer 122 of hydrocarbon distillate in separator 106 has its upper surface maintained at a constant level by means of float control 123 operating on valve 124. As the antifreeze accumulates the interface between antifreeze 119 and distillate 122 rises until a point is reached at which the hydrostatic head of liquid in separator 106 is sufficient to carry the antifreeze over the hump of water leg 120. The pressures in separator 106 and in trap 121 are maintained equal by means of connecting vapor pipe 124. From trap 121 the antifreeze passes through valve 125 controlled by liquid level controller 126 into antifreeze reconcentrator 127 which can be of conventional design and which is not shown in detail. The reconcentrated antifreeze passes through pump 128, line 129 and valve 128 back 40 into the hydrocarbon fluids entering coolers 109 to 111. The distillate passes through valve 124, line 130 and heat exchanger 109, where it serves to lower the temperature of the fluids passing to separator 106.

45 By passing distillate from separator 102 through line 105 to separator 106, I find that the total yield of distillate can be materially increased. Thus, for example, with South Jennings, Louisiana, well fluid, separator 102 can be operated at well head pressure and temperature, 3140 pounds per square inch and 130° F. (without using cooler 101), and separator 106 can be operated at 1200 pounds per square inch and 0° F. With these conditions the total yield of butanes and 55 heavier as liquid formed will be 1.076 gallons per 1000 cubic feet of total propanes and lighter, if distillate is separately withdrawn from separators 102 and 106, while with the arrangement shown in Figure 2, with the distillate from separator 102 passing to separator 106 as reflux liquid material, to alter the phase conditions existing therein in such a manner as to increase the overall efficiency of this part of the process, the total yield becomes 1.109 gallons per 1000 cubic feet 60 of total propanes and lighter.

70 After passing through heat exchanger 109, the temperature of the distillate is additionally increased by means of heater 131. Thus, for instance, this heater can increase the temperature to a value within the range from about 200° F. to about 400° F., for instance 350° F., at about the pressure existing in separator 106 although there is, of course, some slight pressure drop. The purpose of this heating is to drive off a considerable quantity of the methane and ethane con-

tained in the distillate before the pressure of the distillate is reduced as will hereinafter appear. By using heat to drive off methane and ethane under relatively high pressure conditions, for instance 600 to 1200 pounds per square inch, recompression and stabilization costs are greatly reduced. 5

From heater 131 the distillate, now containing a considerable amount of vapor phase material, passes into separator 132 where the distillate and vapors separate. The vapor passes overhead through back pressure control valve 133 while the distillate collects in the bottom of the separator and is withdrawn through valve 134 controlled by liquid level controller 135. This distillate can be passed through valve 136 (valves 137 and 138 being closed) directly into stabilizer tower 139, or additional methane and ethane can be removed by flashing the distillate at a lower pressure prior to introduction into stabilizer tower 139 and this is usually preferable. It can be accomplished by closing valve 136 and opening valves 137 and 138, whereupon the distillate passes into separator 140, the pressure in which is controlled by back pressure control valve 141 at some value substantially less than that existing in separator 132, for instance 300 to 500 pounds per square inch. At this pressure the remaining distillate collects at the bottom of the separator 140 and the low pressure gas passes out through control valve 141 and line 142, whence it passes either through valve 143 for recompression and reinjection into input well A or through valve 144 for other use. 30

35 Valve 138 is controlled by liquid level controller 145 and the distillate removed through this valve or that coming directly from separator 132 passes through heat exchanger 146 where its temperature is raised by indirect heat exchange with the hot stabilized distillate from stabilizer 139. Supplemental heat is then added by means of heater 147 and the distillate passes into stabilizer tower 139 which can be of conventional design and which is preferably operated at from about 200 to about 400 pounds per square inch, for instance 45 about 350 pounds per square inch. Heat is applied to the bottom of the stabilizer by means of heating coil 148 and reflux is provided by means of dephlegmating coil 149. The stabilized distillate passes through valve 150, heat exchanger 146 and cooler 151 to product storage tank 152. 50

55 While I speak of tower 139 as a stabilizer and while it can advantageously be used to produce a finished natural gasoline of marketable vapor pressure, it is preferable to operate it as a depropanizer, sending all the butane and isobutane to product storage tank 152 which should be of the pressure type.

60 Relatively high pressure gases from separator 106 pass through line 118, are recompressed by compressor 153 to a pressure substantially higher than that of the fluids leaving producing well B and then pass through valve 154 into input well A. Similarly the gases at slightly lower pressure from separator 132 pass through line 155, are recompressed by compressor 156 and injected into input well A, and, as previously mentioned, the gases from separator 140 can be recompressed if desired by compressor 157 and similarly reinjected. Likewise the off-gases from stabilizer 139 70 pass through back pressure control valve 158 and line 142 and can then be reinjected with gases from separator 140 by means of compressor 157 or they can be withdrawn through valve 144. 75

Alternatively, of course, a single set of com-

pressors can be used for all of these gases but since they exist at varying pressures it is preferable to use the arrangement shown.

While I have described my invention in connection with certain specific embodiments thereof, it is to be understood that these are by way of illustration and not by way of limitation, and I do not mean to be bound thereby but only to the subject matter of the appended claims.

10 I claim:

1. A method of producing liquid hydrocarbons from fluids produced by a well of the distillate type, said fluids coming from said well at high pressure, which comprises separating liquid hydrocarbons from the remaining gases at high pressure in a first separation zone, cooling said gases while under high pressure, expanding said gases into a second separation zone maintained at a pressure between about 400 pounds per square 15 inch and about 1200 pounds per square inch, expanding the liquid hydrocarbons from said first separation zone into said second separation zone to precipitate additional liquid hydrocarbons in said second separation zone and separating 20 gaseous from liquid hydrocarbons in said second separation zone.

2. A method of producing liquid hydrocarbons from fluids produced by a well of the distillate type, said fluids coming from said well at high pressure, which comprises separating liquid hydrocarbons from the remaining gases at high pressure in a first separation zone, cooling said gases while under pressure, expanding gases from said first separation zone into a second separation zone maintained at a pressure between about 800 pounds per square inch and about 1500 pounds per square inch, expanding liquid hydrocarbons from said first separation zone into said second separation zone to precipitate additional liquid 35 hydrocarbons in said second separation zone and separating gaseous from liquid hydrocarbons in said second separation zone.

3. A method of producing liquid hydrocarbons from fluids produced by a well of the distillate type, said fluids coming from said well at high pressure, which comprises separating liquid hydrocarbons from the remaining gases at high pressure in a first separation zone, cooling said gases while under high pressure, expanding gases from said first separation zone into a second separation zone maintained at a pressure above the

optimum retrograde condensation pressure, expanding liquid hydrocarbons from said first separation zone into said second separation zone as reflux liquid to precipitate additional liquid hydrocarbons in said second separation zone, maintaining a liquid-gas interface in said second separation zone below the point of introduction of said reflux liquid into said second separation zone, and separately withdrawing liquid and gaseous hydrocarbons from said second separation zone. 10

4. A method of producing liquid hydrocarbons from fluids produced by a well of the distillate type, said fluids coming from said well at high pressure, which comprises cooling said fluids to a temperature above that at which hydrates form 15 from said fluids at said pressure, passing the cooled fluids to a first separation zone, separating liquid and gaseous hydrocarbons in said first separation zone, cooling said gases while under high pressure, expanding said gases into a second separation zone maintained at a pressure between about 400 pounds per square inch and about 1200 pounds per square inch, expanding the liquid hydrocarbons from said first separation zone into said second separation zone to precipitate additional liquid hydrocarbons in said second separation zone and separating gaseous from liquid hydrocarbons in said second separation zone. 25

5. A method according to claim 4 in which said gases are expanded in the presence of an anti-freeze material. 30

6. The method of recovering liquid hydrocarbons from a fluid produced by a well of the distillate type which comprises separating the liquid fraction from said fluid at about well head 35 pressure and a temperature above that at which natural gas hydrates are formed at said pressure, admixing said fluid after separation of said liquid fraction with an antifreeze material, passing the resulting mixture to a second separation stage maintained at a temperature within the range from about -50° to about +75° F. and a pressure within the range from about 800 to about 1500 pounds per square inch, supplying said liquid fraction to said second separation stage, 40 independently withdrawing antifreeze material, residual gas and a hydrocarbon condensate from said second separation stage and compressing said residual gas for re-injection into the formation from which said fluid was produced. 50

GEORGE S. BAYS.
